UNITED STATES PATENT OFFICE.

FREDERICK W. LINAKER, OF DUBOIS, PENNSYLVANIA, ASSIGNOR TO THE VULCAN SOOT CLEANER CO., OF PITTSBURG, PA., OF DUBOIS, PENNSYLVANIA, A CORPORATION OF NEW JERSEY.

BOILER-FLUE-CLEANER SYSTEM.

1,138,301.

Specification of Letters Patent.

Patented May 4, 1915.

Application filed November 3, 1914. Serial No. 870,125.

To all whom it may concern:

Be it known that I, FREDERICK W. LINAKER, a subject of the King of England, residing at Dubois, in the county of Clearfield 5 and State of Pennsylvania, have invented certain new and useful Improvements in Boiler-Flue-Cleaner Systems, of which the following is a specification.

This invention relates to improvements in 10 boiler flue cleaner systems, and is designed as an improvement upon the type of flue cleaner systems disclosed in Letters Patent #705,912, granted July 29, 1902 to William Eichelberger; Letters Patent #801,858, 15 granted October 17, 1905 to William Eichelberger; Letters Patent #984,919, granted February 21, 1911 to De Los E. Hibner; and Letters Patent #1,041,141, granted October 15, 1912 to James Moore, all of which Letters Patent embody the broad principle of 20 directing streams of cleaning fluid upon the exterior surfaces of boiler flues, said streams traveling in lines radial to the axis of the distributing pipe from which they issue.

25 The present invention is a special adaptation of the principle above referred to, to boilers of the well-known Stirling type.

The primary object of the invention is to 30 employ one or more suitably located fixed fluid-distributing pipes in combination with one or more rotatable distributing pipes, so that portions of boiler tubes of the Stirling type which have hitherto been inaccessible to the action of the cleaning fluid may be 35 readily reached, and the entire series of tubes thoroughly cleansed of deposits of soot.

A distinguishing feature of the invention 40 is the location of a fixed fluid distributing pipe, or pipes, above the baffle that is between the drums at the top of the boiler, with nozzles projecting through said baffle and extending at an acute angle to the distributing pipe, whereby the upper portions of the inclined boiler tubes may be subjected 45 to the cleaning action of streams of fluid issuing from said fixed pipe or pipes.

Another feature of the present invention 50 is to provide means whereby the superheater structure frequently employed with boilers of this type may be readily cleansed of soot accumulation simultaneously with the cleansing of the boiler tubes.

The construction of the improved apparatus will be more specifically described

hereinafter in connection with the accompanying drawings which constitute a part of this specification, and its novel features will be set forth and defined in the appended claims.

In the drawings: Figure 1 is a vertical 60 side sectional view of a portion of a boiler of the Stirling type with the improved fixed and rotating fluid-distributing pipes applied thereto, and Fig. 2 is a vertical front sectional view of the same.

The reference numeral 1 designates the space between the top 2 of the boiler and the top baffle plate 2' that extends between the drums 3 and 4. The boiler tubes in the type of boiler here shown are disposed in 70 four banks designated by the reference letters A and B.

The numeral 5 designates a distributing pipe, or pipes, for cleaning fluid, which pipes are located in the space 1, above the 75 baffle 2' and are connected by a suitable feed pipe 6 with a source of supply for steam or other fluid cleaning agent. Depending from the under side of each pipe that is employed is a number of preferably equi-distant discharge nozzles 7 extending through the baffle 2' between the circulating tubes 3' of the drums, in position to deliver the cleaning fluid to the space between the upper ends of the boiler tubes of the banks B. These nozzles are extended through the baffle 2' at an acute angle to the axis of the pipe 5, so as to effectually project the cleaning agent upon the upper portions of the tubes in banks B.

Where a superheater structure such as 90 shown at 6' is employed with a boiler of the type shown, it is desirable that such superheater structure be cleaned at the same time as the tubes of the boiler are cleaned. For this purpose, I place a pipe 5' in each space 95 1, similar to the pipes 5, and provide each pipe 5' with nozzles 7 projected through the baffle 2' at an angle or incline corresponding to the inclined position of the superheater structure so that the cleaning fluid 100 is discharged directly onto the top of the superheater and effectually cleanses the upper portion thereof. These pipes 5' are connected to the feed pipe 6 that supplies the pipes 5.

At suitable points with respect to the boiler tubes are disposed a number of revoluble fluid-distributing pipes, twelve of

said pipes being shown in the accompanying drawings each designated by the reference numeral 10. Each of these pipes 10 is provided with a series of orifices or discharge nozzles 11 to direct cleaning fluid from the pipes 10 between and among the various boiler tubes adjacent thereto, and the rotary movement of said pipes insures a variation in the direction of travel of the streams or jets of fluid to insure a cleansing of the entire outer surface area of the boiler tubes.

Any suitable or preferred means may be utilized for effecting the rotary movement of the pipes 10, as for instance, sprocket or hand wheel swivel joints 12 mounted upon said pipes and adapted to be rotated through the medium of a chain.

Steam or other fluid-cleaning agent is supplied to the rotary pipes 10 from any suitable source of supply through feed pipes 13, the specific arrangement and disposition of the pipe connections not entering into the present invention.

From the construction illustrated in the drawing, and hereinbefore described, it will be apparent that the rotary distributing pipes accomplish the cleaning of all but the upper portions of the boiler tubes, and that these portions which are removed from the sweep of streams of fluid issuing from the rotary pipes may be thoroughly cleansed by the fluid discharged from the stationary pipe or pipes 5, while the upper portions of the superheaters are effectually cleansed by the fluid discharged from the pipe or pipes 5'. The present invention therefore, by providing the stationary distributing pipe above the baffle between the drums supplements the interior rotary pipes and together with said pipes provide an efficient and thorough cleaner system. The pipes 5 and 5' being above the baffles 2' are entirely protected from the heat of the furnace, while the pipes 10 are located with respect to the usual baffle of the boiler so as to be protected largely from the heat of the furnace.

The invention is susceptible to various modifications in structural details without departing from the salient feature of employing a stationary fluid distributing pipe at the top portion of the boiler, and hence it will be understood that the invention comprehends and includes all such constructions as may fall within the terms and scope of the following claims.

What I claim as new is:

1. The combination with a boiler having banks of tubes and a baffle above said tubes between the drums of the boiler, of a stationary distributing pipe above said baffle and having nozzles projecting through the baffle to project cleaning fluid onto the upper portions of said banks of tubes.

2. The combination with a boiler having banks of tubes, water drums to which the tubes are connected at their upper ends, and a baffle between said drums, of a fluid distributing pipe above said baffle and having discharge nozzles projected through the baffle at an acute angle to the axis of the distributing pipe for projecting cleaning fluid onto the upper portions of said banks of tubes. 75

3. The combination with a boiler having banks of tubes, water drums to which the tubes are connected at their upper ends, and baffles between said drums, of a stationary distributing pipe located above the baffle and having nozzles projected through the baffle for distributing cleaning fluid onto the upper portions of the banks of tubes, and rotary distributing pipes arranged within the furnace space of the boiler. 85

4. The combination with a boiler having banks of tubes, water drums to which the tubes are connected at their upper ends, a baffle between said drums at the top of the bank of tubes, and a superheater structure of 90 a pair of distributing pipes arranged above said baffle and having nozzles extending downwardly through the baffle, the nozzles of one of said pipes being directed to project cleaning fluid onto the upper portions 95 of the boiler tubes, and the nozzles of the other pipe being directed to project cleaning fluid onto the upper portion of the superheater structure.

5. The combination with a boiler having 100 banks of tubes, water drums to which the tubes are connected at their upper ends, a baffle between said drums at the top of the bank of tubes, and a superheater structure, of a pair of distributing pipes arranged 105 above said baffle and having nozzles extending downwardly through the baffles, the nozzles of one of said pipes being directed to project cleaning fluid onto the upper portions 110 of the boiler tubes, the nozzles of the other pipe being directed to project cleaning fluid onto the upper portion of the superheater structure, and a feed pipe common to both of said distributing pipes.

6. The combination with a boiler having 115 banks of tubes, and baffles at the upper ends of said tubes, of a stationary fluid distributing pipe located above the baffle out of the heat zone of the furnace space and having nozzles projected through the baffle and directed so as to discharge cleaning fluid onto the upper portions of the boiler tubes, a rotary fluid distributing pipe for the tubes within the furnace space, and a feed pipe common to the stationary and rotary pipes. 120

7. The combination with a boiler having banks of tubes, water drums to which the tubes are connected at their upper ends, and a baffle between said drums, of a fluid distributing pipe arranged above said baffle 125

outside the heat zone of the furnace space and provided with nozzles disposed to project a cleaning agent downwardly through the baffle onto the upper portions of the banks of tubes.

8. In a flue cleaner system, the combination with a boiler having banks of tubes, water drums to which the tubes are connected at their upper ends, and a baffle between said drums, of a stationary fluid-distributing pipe located above the baffle so as to be entirely outside the heat zone of the furnace space and having nozzles arranged to project cleaning fluid downwardly through the baffle onto the upper portions of said banks of tubes, a rotary fluid distributing pipe extending transversely of the banks of tubes within the furnace space of the boiler for projecting cleaning fluid onto other portions of said banks of tubes, and a feed pipe common to both of said fluid distributing pipes.

9. In a flue cleaner system, the combina-

tion with a boiler having banks of tubes, water drums to which the tubes are connected at their upper ends, and a baffle between said drums, of a fluid-distributing pipe located above the baffles so as to be entirely outside the heat zone of the furnace space and having nozzles arranged to project cleaning fluid downwardly through the baffle onto the upper portions of said banks of tubes, a second fluid distributing pipe extending transversely of the banks of tubes within the furnace space of the boiler for projecting cleaning fluid onto the other portion of said banks of tubes, and a feed pipe common to both of said fluid distributing pipes.

In testimony whereof I affix my signature in presence of two witnesses.

FREDERICK W. LINAKER.
